UNITED STATES PATENT OFFICE.

THOMAS J. DIXON, OF MADISON, WISCONSIN.

TUBE EXPANDER.

1,412,278.

Specification of Letters Patent. Patented Apr. 11, 1922.

Application filed March 15, 1921. Serial No. 452,489

To all whom it may concern:

Be it known that I, THOMAS J. DIXON, a citizen of the United States, residing at Madison, in the county of Dane and State of Wisconsin, have invented certain new and useful Improvements in Tube Expanders, of which the following is a specification.

My invention has particular reference to improvements is that type of tube expanders 10 in which provision is made for effecting the simultaneous operation of expanding the end of the tube within the flue sheet and flaring and bellng the end of the tube against the tube seat as the said tube end is being expanded or forced outwardly to hold it securely within the flue sheet.

Primarily, my invention has for its purpose to provide a tool of the general character stated, comparatively inexpensive to 20 make, which is of few parts that may be readily assembled for use or taken apart and which will effectively serve its intended purposes.

My present invention also comprehends 25 a construction of parts, that constitutes a tool for expanding and flaring tube ends, which parts are adapted for being compactly combined, simple and strong, and designed for flaring all of the different standard sizes 30 of tubes, from one to six inches, and which also include a simple and improved means for holding the expanding rollers in the desired operative condition, and from becoming detached or separated from the body or 35 stock portion of the tool.

With other objects in view that will hereinafter be explained, my invention embodies, in a tube shaping tool of the character stated, certain peculiar arrangement and combination 40 of parts, all of which will be fully stated in the following detailed description thereof, specifically pointed out in the appended claims and illustrated in the accompanying drawings, in which:

Figure 1 is a top plan view of my improved construction of tube expanding and flaring tool, a preferred arrangement of parts being illustrated.

Figure 2 is a detail longitudinal section of 50 a portion of the body or stock of the tool, the expanding and flaring elements being shown in side elevation, the parts being shown positioned for feeding into the tube end to be expanded and flared.

Figure 3 is a transverse section thereof on the line 3—3 of Figure 2.

Figure 4 is a transverse section on the line 4—4 of Figure 2, and particularly illustrates the means for holding the expanding tool rollers from operative displacement. 60

Figures 5 and 6 are detail views of the flaring disk and the disk bearing box respectively.

Figure 7 is a plan view showing a modified form of my invention, hereinafter referred to. 65

Figure 8 is a detail longitudinal section of a portion thereof on the line 8—8 of Figure 7.

Figures 9 and 10 are detail views of the 70 expanding and the flaring disk members shown in Figures 7 and 8.

Figures 11, 12 and 13 are detail views of modified arrangements of the spring devices used in connection with the preferred arrangement of the tube expanding and flaring members. 75

In the drawings, 1 designates the body or stock of the tool which is provided with the usual axial bore 2 for the reception of the 80 mandrel 3, it being understood that my present type of tube end forming tool is of the self-feeding kind.

The body 1 has a series (three being shown) of longitudinal slots 4 which extend lengthwise thereof and in a slightly diagonal direction, the several slots extending radially, with respect to the central bore 2, with which bore they communicate, as is best shown in Figure 3, by reference to 90 which it will also be seen the outer ends of the slots 4 are slightly restricted, as at 41, to prevent the expanding rollers 5 from dropping out of the body or stock 1, the said rollers, when assembling the parts, being inserted through either end of the body bore 2. 95

Tube expanders of the class to which my present invention relates, as is well known to those skilled in this art, have more or less complicated ways for holding the expanding rollers when in their inoperative position. In my construction of expanding tool, I employ a simple but effective means for holding the expanding rollers 5 in place 105 and adapted for being easily and quickly adjusted to allow for removing the rollers 5, as desired.

By reference to Figure 3, it will be seen that midway each pair of adjacent slots 4, 110 is a screw pin 6, the several screw pins engaging with internally threaded and radi-

ally projected apertures 7 in the body 1, whose inner ends communicate with the bore 2 at the apex or junction of adjacent ones of the slots 4. Such arrangement of 5 parts provides for radially projecting the inner ends of the screw pins 6 within the bore 2 of the stock 1, sufficiently to form stops to hold the rollers 5 from dropping inwardly into the said bore 2, it being apparent 10 that by giving the screw pins a couple of turns back, the rollers 5 can be dropped in line in the axial bore and quickly taken out through the said bore 2 of the body 1.

8 designates a flaring disk, whose function 15 is to flare or turn the end of the tube that projects through the flue sheet. Any number of said disks may be used, preferably one for each roller as shown.

In the preferred form, shown in Figures 20 1, 2 and 5, the flaring member is a cone shaped disk whose smaller end, when the parts are assembled, is adapted for riding against the adjacent tapered end 51 of an expanding roller 5, as is best shown in Figure 25 2.

The disk 8 has an axial stud 80 in the outer or larger face thereof for engaging a bearing socket 90 in a bearing box 9 that slidably engages a radial pocket 11 in the 30 stock 1 and which is normally held against dropping out of the said pocket 11 by a suitable spring device, which may be and preferably is a bent flat spring 12, one end of which extends into the bore 2 of the stock 35 1 and the other end of which rides upon and within a grooved seat 91 in the top of the box 9, as is clearly shown in Figure 2.

The means shown in Figures 1, 2, 3 and 40 4 for flaring or bending back the tube end, is a preferred construction, and presents a practical arrangement of parts for simultaneously effecting the operation of expanding and flaring the tube end but I desire it understood that the said parts, as shown 45 and described, may be readily varied or modified to suit the particular type of tubes for which my improved tool may be especially adapted.

For example, instead of forming the expanding roller 5 with a conical end that provides a bearing for the cone-shaped disk 8, as shown in Figure 2, the outer end of the roller 5 may have a flat face adapted for flatwise engaging the correspondingly 55 shaped end of a roller 85 of a somewhat larger diameter than the roller 5 and whose front end is tapered, as at 86, to provide an inclined portion that projects beyond the tube contacting surface of the expanding roller 5, for turning back the projected end 60 of the tube, as indicated in Figures 7 and 8. In the latter form of my invention, the two rollers 5 and 85 are joined by a pin connection 87, and since a close fit of the roller 85 within a pocket portion 15 of the

stock is thereby possible, need of the spring shown in the form illustrated in Figures 1, 2 and 3, for holding the flaring roller 85 to the work is unnecessary, since the pin connection 87 holds the roller 85 from dropping out of its seat in the stock 1. 70

Instead of using the spring connection 12 as shown in Figures 1 and 2, the spring connection may be in the nature of a flat spring, one end of which bears on the box 9 and 75 whose other end extends over the adjacent portion of the stock and is fastened thereto by a screw bolt 16, as shown in Figure 11. If desired, a spring shaped as in Figures 12 and 13 may be used. In this form, the 80 spring is in the nature of an inverted V-shaped member 17 whose loop portion 17a seats over a heel portion 91a on the back of the box 9 and whose side portions are bowed to slip under the opposite wall of the bore 2 85 just below the socket in which the box fits, as is clearly shown in Figures 12 and 13.

From the foregoing description taken in connection with the accompanying drawings, the complete construction, the manner in 90 which the several parts are cooperatively arranged, and the advantages thereof will be apparent to those familiar with tools of this type, it being understood that to operate my combination tube expanding and flaring tool which, as before stated, is of the self-feeding type, it is only necessary to place the tool into the end of the tube and flared, to a point where the smaller diameter of the flaring disk, or roller, comes into contact with the 100 tube end, as shown in full lines on Figure 2. The mandrel 3 is then placed into the tool stock or body 1 and the rotary motion thereof is started.

The self-feeding action of the mandrel 105 and the rollers forces the body 1, with the roller 5, into the tube and the flaring member into the projected end of the tube, as it is being expanded by the roller 5, and as the disk 8 (or roller 85) revolves its cone-shaped 110 surface engages the end of the tube and flares or bends it back to the position indicated in Figure 2 and in shape for heading, the act of expanding and flaring being accomplished with one operation of the tool. 115

In the preferred form of my invention shown in Figures 1 to 4, the face of the box that abuts the conical end of the expanding roller 5 has its upper edge projected beyond the larger diameter of its abutting flaring 120 disk, to provide a stop that serves to limit the inward feed of the flaring disk 8, as will be understood from the position shown in Figure 2.

What I claim is:

1. In a tube expander, the combination with the body having an axial bore, the said body having at least one pocket that extends radially from the bore through the periphery of the body, an expanding roller mount- 130

- ed in each pocket, means for holding the said rollers from dropping out from the body, other means for holding the rollers from dropping into the bore of the body, one 5 end of one of the expanding rollers being tapered, a tapering mandrel adjustable through the axial bore of the stock and adapted for engaging and expanding rollers and for projecting them to the flue engaging position, a flaring disk, a bearing box removably mounted within the body, the box and the disk having journal and bearing connections, the said disk engaging the tapered end 10 of the adjacent expanding roller and means for holding the box from dropping out of the body.
2. In a tube expander, the combination with the body having an axial bore, the said body having at least one pocket that extends 15 radially from the bore through the periphery of the body, an expanding roller mount-
- ed in each pocket, means for holding the said rollers from dropping out from the bore, other means for holding the rollers from dropping into the bore of the body, one 25 end of one of the expanding rollers being tapered, a tapering mandrel adjustable through the axial bore of the stock and adapted for engaging and expanding rollers and for projecting them to the flue engaging 30 position, a flaring disk, a bearing box removably mounted within the body, the box and the disk having journal bearing connections, the said disk engaging the tapered end of the adjacent expanding roller, means 35 for holding the box from dropping out of the body, the said disk bearing box having its disk engaging face projected beyond the disk whereby to form a stop for engaging the flared end of the tube.

THOMAS J. DIXON.
